UNITED STATES PATENT OFFICE.

GEORG BENICKE, OF OFFENBACH-ON-THE-MAIN, GERMANY.

GRINDING APPARATUS.

No. 842,381.

Specification of Letters Patent.

Patented Jan. 29, 1907.

Application filed May 20, 1904. Serial No. 208,934.

To all whom it may concern:

Be it known that I, GEORG BENICKE, a subject of the Emperor of Germany, residing at Offenbach-on-the-Main, in the Empire of Germany, have invented certain new and useful Improvements Relating to Grinding Apparatus, of which the following is a specification.

This invention relates to grinding apparatus, and more especially for grinding the crank-pins having counter-cranks.

The accompanying drawings represent an apparatus for grinding the crank-pins of locomotive-wheels, whereby the grinding operation may be performed upon the crank when in position upon the wheel; and the invention has for its object to provide a simple construction readily permitting the necessary adjustments.

Figure 1 is a longitudinal section of the apparatus. Fig. 2 is an end view showing the bell-shaped casing. Fig. 3 is a section on the line A B of Fig. 1. Fig. 4 is a sectional plan of the bell-shaped casing in two planes on the line C D of Fig. 2.

The arrangement and operation of the apparatus are as follows:

A cylinder 6, which is bored with an inclined hole and provided with teeth 4, is mounted within a cylindrical casing 5, upon which is mounted a separate lateral box 23, Fig. 3, in which gear-wheels 21 22 are carried. The cylinder 6 is provided with an extension 3 at one end, upon the reduced extremity of which screw-threads are cut and on which a hand-wheel 2, provided integrally upon an internally-threaded sleeve, is mounted, by the operation of which hand-wheel 2 the extension 3 and the cylinder 6 are moved.

In the angularly-bored cylinder 6 another cylinder 1 is mounted, which is provided with a horizontal bore for the purpose of carrying the spindle 15. The cylinder 1 is provided at one end with a flange having a groove 10 therein, in which enters a flange 9, which is mounted upon the end of the cylindrical casing 5, so as to be capable of movement therein, so that thus the spindle 15 may be moved out of the center line of the apparatus. This

movement is effected by turning the hand-wheel 2, whereby the cylinder 6 moves upon the cylinder 1. Therefore inasmuch as the cylinder 6, guided in the cylindrical casing 5, cannot yield the cylinder 1 and the spindle

15 carried thereby is forced to move on the turning of the hand-wheel 2, so that thus on the turning of the hand-wheel 2 the cylinder 1 is moved from the center, which it is permitted to do by the provision of the groove 10. The cylinder 1, upon which the cylinder 6 moves, is connected with the latter by means of a key, which runs in a longitudinal groove 8, provided on the cylinder 1, so that when the cylinder 6 is turned by the gear 21 22 the cylinder 1 and the spindle 15 is also caused to rotate.

Upon the flange 7 of the cylinder 1 a bell-shaped casing 11 is carried, which is connected to the flange aforesaid by means of screws 12, as illustrated. This bell-shaped casing 11 is of such dimensions that the crank 16 has ample space afforded for its reception. Upon the casing 11 a segment-guide 18 is provided, as illustrated in Fig. 2, upon which the grinding-wheel 17 is fixed upon an arm 19, which can be moved in the guide 18 according to requirement.

The spindle 15 is provided at its extremity with a pulley 13, upon which a belt 14 passes, and also upon a pulley 25, which is fitted upon a spindle 24, upon which a pulley 20 is also mounted, around which a cord is passed, which passes also over the coincident pulley 26, which is mounted upon the spindle of the grinding-wheel, so that when the pulley 26 is rotated the grinding-wheel 17 is caused to rotate. This construction is more especially to be seen in the cross-sectional view, Fig. 4.

As soon as the cylinder 6 is set into rotation by the operating-gear the cylinder 1 and the spindle, and therefore also the grinding-wheel, rotate, and at the same time the bell-shaped casing 11, which is in absolute connection with the cylinder 1, must rotate therewith. The grinding-wheel 17 will therefore, besides rotating upon its own axis, turn upon the axis of the spindle 15.

The locomotive-crank 16 (illustrated in Fig. 1 in position to be ground) is, with the wheel, fitted upon a strong head-stock or carrier, which by means of a slide can be laterally moved, and thus adjusted into proper position with reference to the grinding-wheel. The approximate adjustment of the emery-wheel 17 with reference to the work-piece can be effected upon the guide-segment 18, while fine or exact adjustment is effected by means of the hand-wheel 2.

The adjustment of the grinding-wheel with reference to the work-piece can be effected when the wheel is rotating.

It will be understood that the grinding-wheel 17 can be fixed to the left or to the right of the frame.

What I claim as my invention, and desire to secure by Letters Patent, is—

1. A grinding apparatus consisting of a wheel, said wheel having an inclined bore, a cylinder fitting within said wheel and keyed to rotate therewith and to slide therein, means for maintaining said wheel to always rotate upon the same axis, and means for rotating said wheel, means for moving said wheel longitudinally with reference to the said cylinder so as to vary the axial position of the said cylinder with reference to the said wheel, and a grinding-tool and gear mounted on said cylinder, and means for rotating said grinding-tool.

2. A grinding apparatus consisting of a wheel, said wheel having an inclined bore, a cylinder fitting within said wheel and keyed to rotate therewith and to slide therein, means for maintaining said wheel to always rotate upon the same axis, and means for rotating said wheel, means for moving said wheel longitudinally with reference to the said cylinder, said means consisting of a screwed member connected with said wheel, a nut device fixedly mounted so that on rotation thereof axial movement shall be communicated to said screwed member, so as to vary the axial position of the said cylinder with reference to the said wheel, and a grinding-tool and gear mounted on said cylinder, and means for rotating said grinding-tool.

3. A grinding apparatus consisting of a fixed cylindrical casing, a wheel capable of sliding within said casing, said wheel having an inclined bore, a cylinder fitting within said wheel and keyed to rotate therewith, means for maintaining said wheel to always rotate upon the same axis, and means for rotating said wheel, means for moving said wheel longitudinally with reference to the said cylinder so as to vary the axial position of the said cylinder with reference to the said wheel, and a grinding-tool and gear mounted on said cylinder, and means for rotating said grinding-tool.

4. A grinding apparatus consisting of a fixed cylindrical casing, a wheel capable of sliding within said casing, said wheel having an inclined bore, a cylinder fitting within said wheel and keyed to rotate therewith, means for maintaining said wheel to always rotate upon the same axis, and means for rotating said wheel, means for moving said wheel longitudinally with reference to the said cylinder, so as to vary the axial position of the said cylinder with reference to the said wheel, a flange upon the end of said casing, a deep annular recess at the end of said cylinder.

der within which the flange upon said casing lies whereby the said cylinder is fixedly held against longitudinal displacement, and a grinding-tool and gear mounted on said cylinder, and means for rotating said grinding-⁷⁰ tool.

5. A grinding apparatus consisting of a wheel, said wheel having an inclined bore, a cylinder fitting within said wheel and keyed to rotate therewith and to slide therein, means for maintaining said wheel to always rotate upon the same axis, and means for rotating said wheel, means for moving said wheel longitudinally with reference to the said cylinder so as to vary the axial position ⁸⁰ of the said cylinder with reference to the said wheel, a bell-shaped casing mounted upon the end of said cylinder and a grinding-tool and wheel mounted upon said bell-shaped casing and means for rotating said grinding-⁸⁵ tool.

6. A grinding apparatus consisting of a wheel, said wheel having an inclined bore, a cylinder fitting within said wheel and keyed to rotate therewith and to slide therein, means for maintaining said wheel to always rotate upon the same axis, and means for rotating said wheel, means for moving said wheel longitudinally with reference to the said cylinder so as to vary the axial position ⁹⁵ of the said cylinder with reference to the said wheel, a spindle mounted within said cylinder but having its axis parallel to the axis of the said wheel, a grinding-tool and gear mounted upon the end of said cylinder, said gear deriving motion from said central spindle, and means for rotating said central spindle.

7. A grinding apparatus consisting of a wheel, said wheel having an inclined bore, a cylinder fitting within said wheel and keyed to rotate therewith and to slide therein, means for maintaining said wheel to always rotate upon the same axis, and means for rotating said wheel, means for moving said wheel longitudinally with reference to the said cylinder so as to vary the axial position of the said cylinder with reference to the said wheel, a spindle mounted within said cylinder whose axis however, is parallel to the axis of said wheel, a carrier mounted upon the end of said cylinder a counter-shaft mounted parallel with said spindle, an arm mounted upon said support and carrying the grinding-tool, gear for rotating said grinding-tool from said counter-spindle and for rotating said counter-spindle from said main spindle and means for rotating said main spindle.

8. A grinding apparatus consisting of a wheel, said wheel having an inclined bore, a cylinder fitting within said wheel and keyed to rotate therewith and to slide therein, means for maintaining said wheel to always rotate upon the same axis, and means for rotating said wheel, means for moving said

- wheel longitudinally with reference to the said cylinder so as to vary the axial position of the said cylinder with reference to the said wheel, a spindle mounted within said cylinder whose axis is always parallel with said wheel, a support mounted upon the end of said cylinder, a counter-spindle mounted upon said support away from the center of said main spindle, an arm mounted upon said spindle said arm carrying, a boss, a spindle carried within said boss and a grinding-tool mounted upon said spindle, said support having a circular groove and means for adjusting the position of said grinding-tool-carrying arm within said circular groove, so as to bring the tool into various positions with reference to the center of rotation of the cylinder aforesaid, and means for rotating said main spindle and for conveying motion from said main spindle to said counter-spindle and from said counter-spindle to said grinding-tool.
9. In a grinding apparatus such as specified the main spindle for driving the grinding-tool, a counter-spindle arranged away from the axial center line of said main spindle, an arm carried by said support, the grinding-tool carried within said arm, and means for rotating said main spindle for conveying motion from said main spindle to said counter-spindle and from said counter-spindle to said grinding-tool substantially as described.

10. In a grinding apparatus such as specified the main spindle for driving the grinding-tool, a counter-spindle arranged away from the axial center line of said main spindle, an arm carried by said support, the grinding-tool carried within said arm, and means for rotating said main spindle for conveying motion from said main spindle to said counter-spindle and from said counter-spindle to said grinding-tool, said support having a circular slot and means for adjusting and fixing the position of said arm within said circular groove substantially as described. 45

11. In a grinding apparatus such as hereinbefore specified means for longitudinally moving the member through which the rotation of the cylinder is effected consisting of a hollow boss, a recess within said boss, a central spindle, a driving-spindle and means for conveying motion from said driving-spindle to said spindle, said means passing through said recess in said hollow boss, a screw-nut upon said boss, a nut device for coöperating therewith for the longitudinal movement of said boss, substantially as described. 50

In testimony whereof I have signed my name to this specification in the presence of two subscribing witnesses.

GEORG BENICKE.
